GASEOUS DISCHARGE DEVICE

Henry W. Parker, Toronto, Ontario, Canada, assignor to Rogers Radio Tubes, Limited, Toronto, Canada, a corporation of Canada

Application January 4, 1933. Serial No. 650,169

6 Claims. (Cl. 176—122)

My invention pertains to gaseous discharge devices and relates particularly to that class of such devices which are frequently termed tubes, employ no internal electrodes and are chiefly used as sources of modulated light.

An object of my invention comprises producing an improved type of gaseous discharge device of such novel form that the manufacture and operation thereof is so greatly simplified and facilitated that the economic factor is rendered an optimum.

A further object contemplated comprises producing a gaseous discharge device which is extremely simple in construction and yet highly efficient in operation.

A still further object comprises producing a gaseous discharge device which, while of simplified design, functions as a source of light extremely efficiently and effectively in that the light flux is substantially all emitted from one portion of the device.

I accomplish all of the above desirable results and others which will hereinafter be pointed out and discussed, by a novel simplified construction wherein the gas or vapor from a vaporizable substance such as mercury is directed within an enclosing vitreous envelope toward one extremity only of the envelope that the vapor stream may be efficiently and effectively electrostatically shielded and electromagnetically controlled to vary the intensity of the light emitted therefrom.

I am aware that the use of gaseous discharge devices or tubes employing mercury vapor as a source of modulated light has been hitherto suggested and I am familiar with such devices now in use. I have found, however, that all such devices now suggested or in use are quite complicated and unnecessarily elaborate and are therefore expensive to manufacture and difficult to maintain and operate. They also usually involve provisions for water cooling which still further increases the cost of manufacture and operation. I have discovered that by means of the novel construction hereinafter fully described, I am able to produce a gaseous discharge device which may be used as a source of modulated light in many arts, as, for instance, in television, and of such extremely simple design and construction that its manufacture and operation is greatly facilitated, thus rendering the economic factor thereof an optimum.

In the drawing accompanying and forming a part of this specification and in which like reference numerals designate corresponding parts throughout:

Fig. 1 illustrates a partially sectioned elevation of my improved device;

Fig. 2 illustrates diagrammatically a circuit for the use of my devices when employed for

television purposes or any other purpose requiring a modulated source of light.

Referring now to the drawing and particularly to Fig. 1 which is a partially sectioned elevation of a preferred embodiment of my improved device. The envelope 1 is preferably constructed of a transparent vitreous material such as glass or quartz and is formed to have a tubular portion with extremities as 6 and 2 and a well portion 11. A quantity of vaporizable substance 9 such as mercury is maintained in the well portion. A conduit 5 preferably of glass or quartz is provided for substantially closing the opening of the well portion into the tubular portion and is formed to extend substantially axially within the tubular portion of the envelope 1 with the open extremity of the conduit 5 directed toward the extremity 2 of the tubular portion of the envelope 1. The conduit 5 serves to direct vapor of the substance 9 toward the extremity 2 of the envelope 1.

There is provided in the conduit 5, near the union thereof with the well portion 11, an aperture 8, which serves to drain condensed vapor from the tubular portion of the envelope 1 to the well portion 11.

After the substance 9, preferably mercury, is placed in the well portion, the envelope is exhausted and sealed at 7. Around the tubular portion of the envelope 1 near the extremity 2 thereof, I prefer to place a metallic slotted shield 4 which is connected to ground as shown in Fig. 1 and which serves a dual purpose. It acts as an electrostatic shield for the device and further acts to prevent loss of light flux from the walls of the tubular portion of the envelope.

There is provided an inductance 10 surrounding the well portion 11 through which radio frequency currents are conducted to serve as local inductive heating means for the mercury 9 and to thus vaporize the mercury. A further inductance coil 3 surrounds the tubular portion of the envelope and carries modulated radio frequency currents for the purpose of producing and modulating light in accordance with any desired signals such as television signals.

In the operation of my improved device, the mercury vapor evolved from the mercury 9 is blown from the open extremity of conduit 5 and is directed toward the extremity 2 of the envelope 1. This mercury vapor is of high conductivity and at an appreciable pressure and therefore allows currents induced from the inductance 3 to flow therein provided that the inductance 3 is energized by radio frequency currents. The currents induced in the mercury vapor generate large quantities of light flux and this light in my novel design is confined in one portion of the envelope 1 and is practically all emitted from the extremity 2 thereof. The light may be modulated by a modulated radio

frequency current and the modulation of the light is proportional to the instantaneous value of the modulated radio frequency current.

The back wall 6 and in fact all of that portion 5 of the device near the well portion 11, in the operation of the device, remains at a temperature which is insufficient to maintain the mercury at the vapor pressure necessary for the production of the inductive heating effect and the creation 10 of light and the mercury therefore condenses upon the inner walls of this portion of the envelope and especially upon the portion 6 and thus acts as a reflector which with the shield 4 insures that substantially all of the light flux 15 is emitted from the extremity 2 of the envelope.

It will be noted that the well portion 11 is located near one extremity of the tubular portion of envelope 1 and at that extremity furtherest removed from the portion in which the light and 20 heat is generated.

Referring now to Fig. 2 in which I have shown a diagrammatic representation of a circuit utilizing my improved device as a source of modulated light for visualizing modulated radio frequency currents such as are utilized in television 25 and other similar arts, it will be noted that the modulation inductance 3 and the heating inductance 10 are connected in series and to a resonant circuit 16 which is included in the output circuit 30 of the thermionic amplifier 12 provided with a source of anode potential 15 and cathode energizing source 14. Any source of modulated radio frequency current may be connected to the input terminals 13 and impressed upon the grid and 35 cathode of the tube 12 for producing from my improved device modulated light in accordance with the modulations of the radio frequency current applied.

For the sake of clarity I have omitted in Fig. 40 2 the electrostatic shield 4. This, however, I prefer to utilize as it serves not only as an electrostatic shield but also as a means for conserving and directing light flux toward extremity 2 of the envelope 1.

45 It will be noted from the foregoing that by my novel design I am able to reduce a device of this type to the bare essentials necessary to perform the desired result; that by such novel design I clearly simplify, cheapen and facilitate the manufacture and operation of the device and thereby render the economic factor thereof a minimum.

It will be further noted that my device is self-contained, and does not require complicated 55 water-cooling equipment as in the practical design of my device the dimensions of the envelope 1 and its form and proportions are so chosen that the portion thereof including the well portion 11 is maintained at a temperature, when the device is in operation, sufficiently low to insure that the 60 mercury vapor in this portion of the envelope will condense and return as a liquid through aperture 8 to the well portion that the cycle of operation of the device may be continuous without resorting to water cooling and its necessary complications.

While I have illustrated and described a preferred embodiment of my device it is to be distinctly understood that I may modify the form thereof without departing from the spirit or narrowing the scope of my invention.

Having thus completely described my invention, what I claim as new and desire to secure by United States Letters Patent is as follows:

75 1. In a gaseous discharge device, a closed envelope of vitreous material, a well attached to

80 said envelope, a substance adapted to be vaporized in said well, a conduit substantially closing said well and extending within said envelope with the open end thereof directed toward one end of said envelope, an inductance coil surrounding said well and an inductance coil surrounding said envelope.

85 2. In a gaseous discharge device, a closed vitreous envelope comprising, an elongated portion and a well portion, a vaporizable substance in said well portion, a conduit substantially closing said well portion and so positioned within said elongated portion that vapor from said vaporizable substance is directed toward one extremity only of said elongated portion, an aperture leading from said envelope to said well to permit condensed vapor to drain into said well, an electrostatic shield on said elongated portion, an inductance coil surrounding said shield and an inductance coil adjacent said well portion.

90 3. In a gaseous discharge device, a container of vitreous material comprising a tubular portion and a well portion, a vaporizable substance in said well portion, a conduit substantially closing said well portion for directing vapor from said vaporizable substance toward one extremity only of said tubular portion, an aperture in the base of said conduit for draining condenser vapor from said tubular portion to said well portion, an electrostatic shield on said tubular portion and 100 interconnected inductance coils surrounding said electrostatic shield and said well portion.

95 4. In a gaseous discharge device, a container of vitreous material comprising a substantially tubular portion and a well portion, a quantity of 110 mercury in said well portion, means substantially closing said well portion for directing vapor from said mercury toward one extremity only of said tubular portion, means for draining condensed 115 mercury from said tubular portion directly into said well portion, an electrostatic shield on said tubular portion and interconnected inductance coils surrounding said electrostatic shield and said well portion.

120 5. In a gaseous discharge device a container of vitreous material comprising, a substantially tubular portion and a well portion, a quantity of mercury maintained in said well portion, a conduit substantially closing said well portion and formed to extend axially within said tubular portion with the open extremity of said conduit directed toward one extremity of said tubular portion, an aperture in the base of said conduit for draining condensed mercury vapor from said tubular portion direct to said well portion, an 130 electrostatic shield on said tubular portion and interconnected inductance coils surrounding said electrostatic shield and said well portion.

125 6. In a gaseous discharge device, a container of vitreous material comprising a substantially tubular portion and a well portion located near one extremity of said tubular portion, a quantity of mercury in said well portion, a conduit substantially closing said well portion and formed to extend axially within said tubular portion with 140 the open extremity thereof directed toward the opposite extremity of said tubular portion to which said well portion is attached, an aperture in the base of said conduit for draining condensed mercury vapor from said tubular portion into 145 said well portion, an electrostatic shield on said tubular portion and inductance coils surrounding said electrostatic shield and said well portion, respectively.
